DESIGN FOR A COMBINED MICROPHONE AND DISPLAY CASING

Lloyd J. Andres, Chicago, Ill.

Application February 26, 1940, Serial No. 90,537

Term of patent 7 years

To all whom it may concern:

Be it known that I, Lloyd J. Andres, a citizen of the United States and resident of Chicago, in the county of Cook and State of Illinois, have invented a new, original, and ornamental Design for a Combined Microphone and Display Casing, of which the following is a specification, reference being had to the accompanying drawing, forming part thereof.

Fig. 1 is a top plan view of a combined micro-

phone and display casing showing my new design;

Fig. 2 is a front elevational view;

Fig. 3 is a side elevational view.

The rear surface of the display casing is plain.

I claim:

The ornamental design for a combined microphone and display casing, as shown and described.

LLOYD J. ANDRES.
